Inventor
Henry Souttar
By B. Auger, Atty.

UNITED STATES PATENT OFFICE.

HENRY SESSIONS SOUTTAR, OF LONDON, ENGLAND.

SURGICAL NEEDLE.

Application filed March 21, 1922, Serial No. 545,490, and in Great Britain April 7, 1921.

This invention relates to surgical needles and has particular reference to surgical needles such as are used for stitching up cuts and wounds. Such needles are employed with suitable ligatures and hitherto difficulty has been experienced in providing means for connecting the ligatures to the needles in such a way as not to leave any obstructions such as would tend to tear the 5 wound or material being sewn or make a larger incision than is desirable.

According to my invention I construct the needle with the ligature or thread as a substantially integral attachment to it and the 15 invention consists broadly therefore of a surgical needle constructed with a ligature proceeding directly from its end remote from the point, said ligature being so attached as to be a continuation of the needle 20 and substantially integral with it. This may be effected by forming the needle with a tubular end remote from its point in which the end of the ligature is secured, for instance by the application of slight pressure to 25 the tube after the ligature has been inserted, although as will hereafter appear other means of attachment may be adopted.

In the accompanying drawings I have illustrated by way of example certain embodiments of my invention,

Fig. 1 being an elevational view to an enlarged scale of one form of surgical needle.

Fig. 2 is a sectional view thereof.

Figs. 3 and 4 are views similar to Figs. 1 35 and 2, illustrating a modified construction.

Referring to these drawings the numeral 1 designates a solid steel or other pointed end and 2 designates a tubular end which in the case of a surgical needle is preferably of 40 silver. This tube 2 is connected at one end to the reduced end 3 of the pointed member 1 remote from the point and the other end of the tube has attached to it the ligature or thread 4. It will be noted that the end 3 45 is reduced so that when the tube 2 is in position its walls will be flush with the member 1. The tube 2 may be attached to the member 1 by pressure, soldering or otherwise and to the ligature or thread by pressure, cementing or other suitable process.

In the modification shown in Figs. 3 and 4, the pointed member 1 is reduced at 3 as before to accommodate the tube 2 but its extremity 5 is still further reduced and provided with a spike or point 6 upon which the ligature or thread can be anchored prior

to the application of the tube. By this means the ligature or thread is securely held. It should be noted that the foregoing are given by way of example and do not exhaust the possible forms needles in accordance with the invention may take in practice.

The needle may be of circular section as shown, but it may also in some cases be of other sections such as square or triangular 65 in which case the tubular end will be hollow member which may conform in shape to the body of the solid member but will preferably be cylindrical and the body of the solid member so formed as to gradually merge to 70 the cylindrical where it meets the tube. Moreover, the term needle hereinbefore employed is to be regarded as including both straight and curved needles, lacing threaders and like articles.

By means of the foregoing invention sewing or threading of any character whatever may be more easily done, because the ligature or thread is always single; further, the aperture made by the needle will allow a ligature of the same size as the needle to follow through without any further force being used than is necessary to push or to draw the needle through the body or any other material to be sewn.

Heretofore it has been proposed in such articles as sacking needles to provide means for holding the end of a cord, rope or the like in an axial bore provided in an enlarged end of the needle. In some cases the 90 end of the cord is held in a gripper adapted to screw into the inner end of the axial bore in the enlarged end of the needle; in other cases the enlarged end of the needle is provided with lateral holes by means of 95 which a thread can be passed laterally through the cord then along the side of the needle and through another pair of lateral holes. Of course none of these methods would be practical if applied to surgical 100 needles and my invention does not contemplate any such arrangement.

What I claim and desire to protect by Letters Patent, is:

1. A surgical needle comprising a stem 105 having a solid reduced portion at the end remote from the point, a ligature of a diameter substantially equal to the reduced portion of the needle, and a tube in the bore of which the ligature is secured and arranged 110 for attaching said ligature to the reduced portion of the needle, said tube having plane

parallel sides of uniform section throughout, the outer diameter of the tube being the same as that of the adjacent end of the needle stem so as to present a continuous surface.

- 5 2. A surgical needle comprising a stem having a point at one end and a reduced portion at the other end, a ligature and means for attaching said ligature to the reduced end of the needle comprising a spike or point 10 projecting from said reduced portion upon which the ligature is anchored and a tube which tightly embraces both the ligature and the reduced portion of the needle, the outside diameter of the tube corresponding to the 15 outside diameter of the adjacent end of the

needle stem so as to present a continuous surface.

3. A surgical needle comprising a stem having a solid reduced portion at the end remote from the point, a ligature of diameter substantially equal to the reduced portion of the needle, and a tube attached at one of its ends to the reduced portion of the needle and at its other end to the ligature, the outer diameter of the tube being the same as that of the adjacent end of the needle stem so as to present a continuous surface.

In witness whereof I affix my signature.

HENRY SESSIONS SOUTTAR.
